UNITED STATES PATENT OFFICE.

WILBER PROFFITT AND GILBERT H. BROOKS, OF MARS, PENNSYLVANIA.

AUTOMATIC GAS-SHUT-OFF VALVE.

1,034,298.

Specification of Letters Patent. Patented July 30, 1912.

Application filed March 13, 1912. Serial No. 683,550.

To all whom it may concern:

Be it known that we, WILBER PROFFITT and GILBERT H. BROOKS, citizens of the United States of America, residing at 5 Mars, in the county of Butler and State of Pennsylvania, have invented certain new and useful Improvements in Automatic Gas-Shut-Off Valves, of which the following is a specification, reference being had 10 therein to the accompanying drawing.

This invention relates to an automatic gas shut-off valve, and more particularly to that class of valves designed for insuring the safe use of stoves, burners and other structures utilizing gas, either in its natural or 15 artificial form, as a fuel.

The primary object of our invention is to provide a diaphragm actuated valve that is positive in its action, durable, applicable 20 to various gas pipes or lines, and highly efficient for the purposes for which it is intended.

Another object of this invention is to provide a valve of the above type wherein 25 simple and effective means is employed for locking the valve in a closed or shut off position, until the valve is manually opened, thereby preventing an access of pressure 30 from opening the valve.

A further object of this invention is to provide a valve of the above type that eliminates the asphyxiation of persons who leave 35 stoves and burners burning during sleeping hours, the asphyxiation being caused by a reduction in the pressure of gas or a complete shut off of the same which extinguishes the flame, and then by a resumption of the 40 gas, the same escapes and asphyxiates the persons in the compartment in which the stove or burner is located.

With the above and other objects in view, the invention resides in the novel construction, combination and arrangement of parts to be hereinafter specifically described and 45 then claimed.

Reference will now be had to the drawing, wherein:

Figure 1 is a side elevation of a valve in accordance with this invention, Fig. 2 is a 50 front elevation of the same, Fig. 3 is a longitudinal sectional view of the valve, and Fig. 4 is a plan of the same.

The reference numeral 1 denotes a globular valve body having connections 2, 3 and 55 4, and a horizontal partition 5 having a valve seat 6, said globular valve being of

the ordinary and well known type. Tapped into the connection 2 is a pipe 7 having a coupling 8 for a gas inlet pipe 9, and tapped into the connection 3 is a similar pipe 10 60 having a coupling 11 and a gas outlet pipe 12. These elements are also of the ordinary and well known construction, and mounted in the connection 4 is a cap 13 having the upper end thereof screwed, as at 14. The 65 cap 13 has a vertical bore 15 for a valve stem 16, said stem having a valve 17 adapted to engage the valve seat 6.

Screwed upon the upper threaded end of the cap 13 is a sectional diaphragm casing 70 comprising a bottom section 18 and a top section 19, said top section having a central opening 20 for the upper end of the valve stem 16. Between the sections 18 and 19 there is arranged a diaphragm 21, made of 75 flexible metal or other material, and said diaphragm is retained between the sections 18 and 19 by rivets 22 or other fastening means connecting the peripheral edges of said sections. The valve stem 16 is connected to the diaphragm 21 by lock nuts 23 arranged upon the upper and lower sides of 80 said diaphragm, whereby the diaphragm and said valve stem will move in unison. The bore 15 of the cap 13 has a groove 85 establishing communication between the sectional diaphragm casing 16 and the valve body 1, whereby gas above the horizontal partition 5 can enter the diaphragm casing.

Formed integral with diametrically opposed edges of the casing section 19 are brackets 25 and 26. Arranged in the bracket 25 is a rock shaft 27 and mounted upon said rock shaft is a lever 28 and a crank 29. The lever 28 extends through a 95 slot 30 provided therefor in the bracket 26, said lever also extending through a slotted head 31, carried by the upper end of the valve stem 16. Pivotaly connected to the crank 29, as at 32 is a latch 33 that extends 100 into an opening 34 provided therefor in the bracket 26. The outer side of the bracket 26 has a guide member 35 beneath the opening 34 and pivotaly connected to the outer side of said bracket, as at 36 is a weighted 105 locking member 37 having a flat edge 38 and a cam edge 39.

When the gas is to be burned, the shut off valve is set in the position shown in Figs. 1 and 2, that is, with the lever 28 in 110 an elevated position, the end of the arm 33 protruding through the opening 34 and the

weighted locking member 37 engaging the protruding end of the arm 33. The locking member is retained in the position shown in Fig. 2 by the flat edge 38 thereof contact-
5 ing with the protruding end of the arm 33 and with the lever 28 in an elevated position, the valve 17 is raised and gas can flow through the globular valve body 5 into the outlet pipe 12. The gas also passes
10 through the groove 24 of the cap 13 and retains the diaphragm in an elevated or ex-
tended position. When the pressure of gas
passing through the globular valve body 1
is reduced or the gas completely shut off,
15 the diaphragm 21 assumes its normal hori-
zontal position, thereby lowering the lever
28, which through the medium of the rock
shaft 27 and the crank 29 shifts the arm
33. The arm is retracted from its pro-
20 truding position in the bracket 26, and the
weighted locking member 37 is released, said
member swinging through the guide 35 and
over the end of the lever 28, the cam edge
39 of said locking member engaging the
25 upper edge of the lever. When the gas is
turned on or the pressure restored, the
valve 17 cannot elevate by reason of the
valve stem 16 being held in a lowered pos-
ition by the lever 28 and the lever 28 in a
30 locked position by the member 27. To ob-
tain a supply of gas it is necessary that the
locking member 37 be manually shifted
and set in the position shown in Fig. 2.
35 Should it not be desired to use the auto-
matic feature of the valve, the locking mem-
bers 37 can be completely swung to the left

hand side of the bracket 26, as shown in
Fig. 2, thereby allowing the lever 28 to
remain normally elevated with the valve 17
open.

40 From the foregoing it is thought that the
operation and utility of our invention will
be apparent without further description,
and while in the drawing there is illus-
trated a preferred embodiment of the in-
vention, it is to be understood that the
structural elements thereof are susceptible
to such variations as fall within the scope
of the appended claim.

45 What we claim is:—

50 In an automatic gas shut off valve, the
combination with a globe valve connected
to a supply of gas, a diaphragm casing in com-
munication therewith, and a diaphragm ar-
ranged within said casing and controlling
55 the operation of said valve, of a pivoted
lever carried by said diaphragm casing and
movable with said diaphragm, a bracket
carried by said diaphragm casing, an arm
movable with said lever and extending
60 through said bracket, and a pivoted lock-
ing member carried by said bracket and
held by said arm and adapted to be re-
leased thereby to swing over said lever and
lock said lever in a lowered position.

65 In testimony whereof we affix our signa-
tures in the presence of two witnesses.

WILBER PROFFITT.
GILBERT H. BROOKS.
